CONSOLE GASOLENE DISPENSING UNIT

Leonard N. Freed, Bartlesville, Okla., assignor to Cities Service Oil Company, Bartlesville, Okla., a corporation of Delaware

Filed June 29, 1964, Ser. No. 80,621

Term of patent 14 years

(Cl. D52—2)

Fig. 3

FIGURE 1 is a perspective view of a console gasoline dispensing unit illustrating one side and one end and embodying my new design; the opposite side, not shown, being substantially the same as the corresponding side and the opposite end, not shown, being substantially the same as the corresponding end but without the fittings.

FIGURE 2 is a sectional view taken along the line 2—2 of FIGURE 1.

FIGURE 3 is a perspective view of another embodiment of my design illustrating one side and one end thereof, the opposite side, not shown, being substantially the same as the corresponding side and the opposite end, not shown, being substantially the same as the corresponding end.

The essential features of the design reside in the portions shown in full lines.

I claim:

The ornamental design for a console gasoline dispensing unit, substantially as shown and described.
